PARTITION SUPPORTING BRACKET

Pierre H. Meyer, Mount Vernon, N. Y.

Application June 29, 1938, Serial No. 216,520

9 Claims. (Cl. 312—140.3)

This invention relates to shelf, counter or wall displays and particularly to the provision of means for supporting panels in different positions of adjustment forming partitions on a shelf or counter display or shelves in a wall display; and the object of the invention is to provide a panel supporting means involving two similar or substantially similar devices each having wall portions arrangeable in close proximity to each other 10 to form a channel to receive a partition strip or shelf with means on each device for securing the same to a predetermined support, and further to provide devices having means for adjustably mounted the same in connection with an apertured support; a further object being to provide a panel supporting means comprising two similar or substantially similar devices each formed from a single sheet of material fashioned to form a substantially L-shaped element and to employ 15 a pair of said devices in opposed relationship spaced to receive a panel therebetween; and with these and other objects in view, the invention consists in a device of the class and for the purpose specified, which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a sectional side elevation of my supporting means, indicating in dotted lines the position of a panel relative thereto.

Fig. 2 is a sectional view on the line 2—2 of Fig. 1 showing a panel in position.

Fig. 3 is a perspective view of one element of my device detached; and,

Fig. 4 is a view similar to Fig. 1 showing a modified form of supporting means.

To illustrate one use of my device, I have shown a counter or shelf 10 having an elongated channel 11 in which is arranged a channeled strip 12 having apertures 13 at regularly spaced intervals longitudinally thereof. The strip 12 may be secured in the channel 11 by any suitable means. The upper surface 12a of the strip 12 in the construction shown is arranged slightly below the upper surface of the counter or shelf 10.

Arranged on the channeled strip 12, I have shown my panel supporting means as comprising two similarly shaped members or devices 14 having base portions 15 and panel engaging portions 16 arranged at desired angles with respect to each

other. In the construction shown in the drawing, the panel engaging portions 16 are arranged at angles of slightly more than 90° to the base portions 15. The base portions 15 have downwardly extending side edges 17 forming channels adapted to straddle the channeled strip 12 as clearly seen in Fig. 2 of the drawing. Between the downwardly extending edges 17 of the portions 15 are spaced tongues 18 projecting downwardly and in a direction away from the panel engaging portions 16. The tongues 18 in the construction shown are formed from the material of the elements 14 by stamping out sections of the portions 15 leaving apertures 19 therein; and it will be apparent that the spacing of the tongues 18 corresponds to the spacing of predetermined apertures 13 in the channeled strip 12. The curved contour of the projecting tongues 18, which is clearly apparent in Fig. 1 of the drawing, provides for resilient wedge-like engagement between the tongues 18 and the mounting strip 12 insuring positive support of the member 14 thereon while at the same time allowing for slight irregularities in said members or mounting strip.

In mounting a partition or shelf panel by my improved means, the tongues 18 of the elements 14 are first inserted in adjacent pairs of apertures 13 in the channeled strip 12 as clearly seen in Fig. 1. The panel 20 is then inserted between the panel engaging portions 16 of the elements 14. It will be noted that the upper ends 16' of the portions 16 are slightly curved or flared outwardly to permit the insertion of the panel 20; and it will further be noted that the elements 14 when arranged in adjacent pairs of apertures 13 are disposed in such spaced relation that the upper ends of the portion 16 will tightly or firmly engage the panel 20 with the portion 16 under tension. At the same time, slight clearance is provided at the base of the portion 16 as seen at 21 in Fig. 1 of the drawing to allow for the slight variation in the thickness of material used in the panel 20.

It will be noted that each element 14 is stamped from a single sheet of material and that in stamping the downwardly projecting edges 17 of the portion 15, the width of the portion 15 is slightly reduced as clearly seen in Figs. 2 and 3. By forming the sheet of material having the portion 16 integrally joining the portion 15 throughout the irregular contour thereof, the resulting element becomes very rigid. There is, however, sufficient spring in the material of the portion 16 so that when it is arranged at an angle of slightly more than 90° to the portion 15 as previously de-

5

scribed, the portion 16 may be flexed to substantially the 90° or perpendicular position. Thus when a pair of elements 14 are mounted as shown in Fig. 1, the portions 16 form very effective 5 spring clamps for retaining the panel 20 firmly in position. It will be apparent that the insertion of the panel 20 securely locks the elements 14 to the strip 12 preventing removal of the elements therefrom as long as the panel is in position therebetween.

In Fig. 4 of the drawing, I have shown a modified form of my supporting means adapted to support a panel 20a at a predetermined angle to an inclined counter or shelf 10a having a mounting strip 12a arranged in a channel 11a therein. The supporting means comprises members 14a, 14b, having mounting portions 15a, 15b, and panel engaging portions 16a, 16b. The members 14a, 14b, have projections 18a, 18b, in the mounting 15 portions 15a, 15b thereof adapted to engage apertures 13a in the mounting strip 12a, and the said members are otherwise similar to the members 14 except for the angular arrangement of the mounting and panel engaging portions thereof. The angles 22a, 22b, formed between the mounting and panel engaging portions of the members 14a, 14b, respectively, are substantially complementary angles, 22a being an obtuse angle and 22b being an acute angle. 20 Each of these angles, however, will be slightly greater than the complement of the opposing angle to provide for the resilient engaging of the panel 20a between the portions 16a, 16b.

While for purposes of illustration I have shown 35 in the drawing two angular arrangements of a panel 20, 20a with respect to a supporting surface 10, 10a, it will be understood that my supporting means may be used to support a partition or shelf panel arranged at any desired angle 40 to a predetermined supporting surface. The length and width of the panel may be varied depending upon the desired use thereof and may be composed of glass, wood, fibre, or other material generally used in counter or shelf displays. 45 The panel engaging portions of my supporting means may be varied in width or length to render said means more effective in supporting panels of various sizes and shapes. It will further be apparent that while the device is designed primarily for supporting a panel when the elements 14 are arranged in adjacent pairs of apertures in the mounting strip 12, it is likewise adapted by arranging the elements 14 in spaced 50 pairs of apertures to be used in supporting wider rails or platforms in position on a counter or other surface.

Having fully described my invention what I claim as new and desire to secure by Letters Patent, is:

60 1. A means for supporting panels of the class described for use in counter and wall displays, said means comprising a pair of similar elements an elongated strip of channel cross sectional form having transverse apertures arranged longitudinally thereof for mounting said elements, each element comprising a mounting portion and a panel engaging portion arranged at an angle thereto, and said mounting portion being channeled to conform to the contour of said strip and 65 having longitudinally spaced projecting tongues co-operating with the apertures of said mounting strip to retain the element against displacement and against movement in one direction thereon.

70 2. A panel supporting means of the class described comprising a pair of similar elements and

a mounting strip for said elements having apertures arranged longitudinally thereof, each of said elements comprising a mounting portion having projecting tongues registering with spaced apertures in said mounting strip, a panel engaging portion arranged at an angle to said mounting portion, the angle formed between the mounting and panel engaging portions of one element being slightly greater than the complement of the angle formed between said portions of the other element, and the angles formed between the mounting and panel engaging portions of said elements being equal whereby a panel supported therebetween will be disposed at right angles to the supporting surface.

15 3. A panel supporting means of the class described comprising a pair of similar elements and a mounting strip for said elements having apertures arranged longitudinally thereof, each of said elements comprising a mounting portion having projecting tongues registering with spaced apertures in said mounting strip, a panel engaging portion arranged at an angle to said mounting portion, the angle formed between the mounting and panel engaging portions of one element being 20 slightly greater than the complement of the angle formed between said portions of the other element, and said elements being arranged in opposed relationship on said mounting strip with the panel engaging portions thereof spaced to receive a panel therebetween.

30 4. A panel supporting means of the class described comprising a pair of similar elements and a mounting strip for said elements having apertures arranged longitudinally thereof, each of said elements comprising a mounting portion having projecting tongues registering with spaced apertures in said mounting strip, a panel engaging portion arranged at an angle to said mounting portion, the angle formed between the mounting and panel engaging portions of one element being slightly greater than the complement of the angle formed between said portions of the other element, the mounting portions of said elements being rigid and the panel engaging portions being resilient throughout the length thereof, and said elements being arranged in opposed relation on said mounting strip spaced to resiliently engage a panel therebetween.

45 5. A panel supporting means of the class described comprising a pair of similar elements and a mounting strip for said elements having apertures arranged longitudinally thereof, each of said elements comprising a mounting portion having projecting tongues registering with spaced apertures in said mounting strip, a panel engaging portion arranged at an angle to said mounting portion, the angle formed between the mounting and panel engaging portions of one element being 50 slightly greater than the complement of the angle formed between said portions of the other element, the mounting portions of said elements being rigid and the panel engaging portions being resilient throughout the length thereof, said elements being arranged in opposed relation on said mounting strip spaced to resiliently engage a panel therebetween, the projecting tongues in the mounting portions of said elements being curved downwardly and in a direction away from the panel engaging portions thereof and forming 55 a wedge-like members securely engaging said mounting strip when a panel is arranged between said elements.

60 6. A supporting means for disposing a panel at a predetermined angle to a supporting surface 70

having an apertured mounting strip arranged thereon, said means comprising a pair of similar elements each having angularly disposed mounting portions and panel engaging portions, the angle formed between said portions of one element being slightly greater than the complement of the angle formed between said portions of the other element, projecting tongues in the mounting portions of said elements extending 5 downwardly and in a direction away from the panel engaging portions thereof, said elements being secured to said mounting strip by said projecting tongues registering with spaced apertures therein, and the panel engaging portions of said 10 elements being arranged in opposed relation to each other spaced to receive a panel therebetween.

7. A device of the character described comprising an L-shaped body of sheet material, one end portion of said body having longitudinally 15 spaced projecting hook members forming means for attaching said end portion to a suitable support, and the other end portion of said body comprising a resilient plate member arranged at an angle of substantially 90° to said first named end portion and projecting therefrom in a direction opposite to the projection of said hook members 20 from said first named end portion.

25

8. As an article of manufacture adapted for use in retaining a panel in connection with a mounting member, a supporting element comprising a mounting portion and a resilient plate-like panel engaging portion at one end thereof arranged at a predetermined angle thereto, means for detachably securing the mounting portion of said element to said mounting member, and said last named means comprising hook-shaped projections extending toward the opposed end of said 10 element and adapted to be slidably urged into close engagement with said mounting member when a panel is supported by said element.

9. A panel positioning and retaining means comprising a support, a pair of similar panel engaging elements, each element comprising a substantially L-shaped body having a mounting end portion and an angularly extending panel engaging portion, said mounting end portion having spaced coupling elements for engaging said support in retaining the elements in connection therewith, and means on said support whereby two of said elements may be arranged in juxtaposition to form a panel receiving passage between the adjacent panel engaging portions 25 thereof.
